UNITED STATES PATENT OFFICE.

GEORGE HERBERT BRINTON, OF ELWYN, PENNSYLVANIA.

CORKSCREW AND CORK-HOLDER.

SPECIFICATION forming part of Letters Patent No. 723,581, dated March 24, 1903.

Application filed July 30, 1902. Serial No. 117,667. (No model.)

To all whom it may concern:

Be it known that I, GEORGE HERBERT BRINTON, a citizen of the United States, and a resident of Elwyn, in the county of Delaware and State of Pennsylvania, have invented a new and Improved Corkscrew and Cork-Holder, of which the following is a full, clear, and exact description.

The object of this invention is to provide a novel simple device that is well adapted for use to pull the cork of a bottle and also to retain the cork in the neck of the bottle if the cork is replaced and the holder adjusted for such a purpose.

The invention consists in the novel construction and combination of parts, as is hereinafter described, and defined in the appended claims.

Reference is to be had to the accompanying drawings, forming a part of this specification, in which similar characters of reference indicate corresponding parts in all the views.

Figure 1 is a side view of the device arranged to serve as a corkscrew. Fig. 2 is a broken reverse plan view of the same having parts adjusted to serve as a holder for a bottle-cork, and Fig. 3 is a side view of the device applied to retain a bottle-cork within the neck of the bottle.

In the drawings, which represent the construction and application of the device, 5 indicates the spirally-twisted body of a corkscrew, terminating at its free end in a tapered point *a*, as usual. At the opposite end of the body 5 the diametrically-enlarged screw-threaded stem 6 is formed or secured so as to project from the spiral formation in the same plane with the axis of the latter. A cross-bar 7 is mounted upon and secured to the stem 6 adjacent to the coiled body 5, said cross-bar being slotted longitudinally from each end toward the center, said slots *b* that are in alinement being formed in the same vertical plane.

Two arms 8 of similar form are respectively pivoted in the slots *b* at equal distances from ends of said arms, as indicated at *c*, said pivots being preferably positioned near the ends of the cross-bar 7. The inner ends of the arms 8, that approach the threaded stem 6

when the outer ends thereof are rocked upwardly, may with advantage have a slope formed on each one of equal degree, these slopes *d* impinging upon similar slopes *e*, that define the inner ends of the slots *b*, and it will be evident that the contact of said mating slopes will limit the upward rocking movement of the arms 8, as shown in Fig. 1. The arms 8 are preferably curved edgewise an equal degree, so that they, together with the 60 slightly-bent members of the cross-bar 7, will assume the form of a flattened arch when the arms are fully spread apart and the shoulders *e* are impinged by the sloped ends *d*, as appears in Fig. 1. Upon the ends of the arms 65 8 that are outermost when said arms are rocked apart a locking-lug *g* is formed on each one, these lugs of like shape projecting toward the corkscrew-body 5 when the arms are rocked downward at their outer ends, and 70 their end walls *h* may with advantage be concaved, as shown in Fig. 2.

Upon the threaded body of the stem 6, which projects above the cross-bar 7, a clamping-nut 9 is screwed, this nut having a peripheral 75 flange 10 thereon at its upper end, said flange being roughened on the edge to afford means for tightly gripping and turning the nut when this is desired. Below the flange 10 the body of the clamping-nut 9 is tapered to give it 80 coniform shape, the smaller diameter being at the lower end of the nut-block, and it will be seen in Fig. 1 that to arrange the device for use as a corkscrew the arms 8 are fully diverged, so that the ends *d* contact with the 85 shoulders *e*. The nut-block 9 is then screwed down, so that it presses upon the top edges of the arms 8 at their inner ends, which will obviously hold the arms fully extended. The corkscrew may now be readily inserted in the 90 usual manner into the cork *A* of a bottle-neck *B* and the cork withdrawn by a pull on the arms 8.

In case it is desired to carry a bottle containing liquid of any kind upon the person 95 and secure the cork against accidental displacement, this may be conveniently and reliably effected by applying the improvement as a holder for the cork.

In Fig. 3 I have shown the application of 100

the device arranged as a cork-holder to secure the cork A in the neck B of a bottle. As usual in the formation of bottles for trade purposes, the top edge of the bottle-neck B is provided with a peripheral bead B'.

In applying the device the nut-block 9 is first screwed toward the free end of the stem 6, so as to permit the arms 8 to be swung down. Now assuming that the cork A is inserted in the bottle-neck B, as indicated by dotted lines in Fig. 3, while the corkscrew-body 5 is screwed into the cork so as to properly dispose the lugs g of the arms 8 below the bead B', it will be seen that by rocking the lugs so that their concave edges h contact with the bottle-neck below the bead B' and then screwing the nut-block downward the coniform body of the latter will press against the sloped edges d of the arms 8 and lock the lugs g below the bead B'.

The improvement when adjusted to serve as a cork-holder is very advantageous, as it may be used to secure the cork of a bottle that may hold aerated liquid, volatile spirits, or gaseous liquor, such as champagne-wine, and retain a portion of the contents after part has been decanted.

A traveler or tourist who may have occasion to carry a bottle of liquor or a medicinal preparation can by employment of the improvement readily withdraw a tight cork and after using part of the contents of the bottle adjust the appliance for securely holding the cork in the bottle to retain the remaining portion of its contents therein and avoid spilling any of the same.

Having thus described my invention, I claim as new and desire to secure by Letters Patent—

40 1. The combination of a corkscrew, a transverse bar formed thereon, arms pivoted near the ends of the transverse bar, vertically-adjustable means engaging with the upper end portions of the arms for holding the latter in a folded or vertical position relatively to said body portion, said vertical adjustable means also being adapted to engage with the side edge portions of the pivoted arms for holding the latter in a radially-extending horizontal 50 position relatively to said body portion, substantially as set forth.

2. The combination with a corkscrew-body, and a screw-threaded stem extending from the upper end of said body, a transverse bar 55 held on the corkscrew-body, arms pivoted to said transverse bar, said arms being provided with engaging lugs at their lower ends, the upper ends of said arms being beveled outwardly relative to each other, and a nut-block 60 vertically adjustable upon the screw-stem of the device adapted to engage with the aforesaid beveled ends of the arms to retain the latter in a vertical or folded position relatively to the body portion, said block also 65 being adapted to engage with the side edges

of said arms to hold them open or in a horizontally-disposed position, relatively to the body portion, substantially as set forth.

3. A corkscrew comprising a spiral body portion, a screw-stem at one end of the spiral formation, a conical nut vertically adjustable upon said stem, and folding arms pivoted on projections extending from the corkscrew-body, said arms being adapted to be laterally projected by pressure of the nut thereon, substantially as set forth.

4. A corkscrew comprising a spiral body, a threaded stem extending from one end of said body, a nut-block coniform in its body and vertically adjustable upon the threaded stem, 80 a transverse bar centrally held on the corkscrew-body, curved arms pivoted to said bar at a point intermediate their end portions, the lower end portions of said arms being provided with laterally-extending engaging lugs, 85 the lower ends of said arms being inclined or beveled oppositely to each other, said arms being held in a horizontal or extended position by engagement of the nut with the edge portions thereof and being held in a folded 90 position by the pressure of the nut upon the inclined or beveled upper edges thereof, substantially as set forth.

5. A corkscrew comprising a spiral body, adapted to screw into the cork of the body, a 95 threaded stem extended from one end of the spiral body, a frusto-conical nut upon said stem, a transverse bar fixed upon the spiral body, said bar being slotted from each end toward the center, said slots terminating in 100 inclined or sloping shoulders, curved arms provided at their end portions with engaging lugs pivoted to said bar at a position intermediate their length, each arm having its inner end inclined or beveled, said inclined ends 105 being adapted to be held against the inclined faces of the bar by means of the pressure of the nut, said nut also being adapted to engage said inclined faces of the arms to bring the lugs into locking engagement with the 110 bead of a bottle-neck, substantially as set forth.

6. The combination of a corkscrew having arms pivoted near the upper end to swing in the vertical plane and a threaded stem above 115 said arms, and a nut on said stem adapted to bear downward on the arms and hold them in the raised position.

7. The combination of a corkscrew having arms pivoted near the upper end to swing in 120 the vertical plane and a threaded stem above said arms, and a nut on said stem adapted to bear downward on the arms and hold them in the raised position, the said arms having lugs at their free ends to clamp a bottle-neck 125 when the arms are in the lower position.

8. The combination with a corkscrew having a threaded upper end, of a nut thereon having a coniform surface, and arms pivoted 130 to the corkscrew to swing in the vertical

plane, the inner ends of the arms being inclined and the nut serving to hold the arms in either the raised position, by bearing downward against the top of said arms, or in the lower position by an engagement of the coniform sides of the nut against the inclined ends of the arms.

In testimony whereof I have signed my name to this specification in the presence of two subscribing witnesses.

GEORGE HERBERT BRINTON.
